US00D618359S

(12) **United States Design Patent**
Einarsson

(10) **Patent No.:** **US D618,359 S**
(45) **Date of Patent:** **** Jun. 22, 2010**

- (54) **EXPANSION PART FOR ORTHOPEDIC DEVICE**
- (75) Inventor: **Palmi Einarsson**, San Juan Capistrano, CA (US)
- (73) Assignee: **Ossur HF**, Reykjavik (IS)
- (**) Term: **14 Years**
- (21) Appl. No.: **29/343,470**
- (22) Filed: **Sep. 14, 2009**
- (51) LOC (9) Cl. **24-01**
- (52) U.S. Cl. **D24/192**
- (58) **Field of Classification Search** D24/188-192; 602/5-7, 16, 21-23, 27-29, 64-65; 128/882; D21/771-772; D2/891, 904; D11/200, 218; D8/367, 383; 24/197, 200; 36/50.1, 114, 36/117.2, 118.2; 2/323

(57) **CLAIM**

The ornamental design for an expansion part for an orthopedic device, as shown and described.

DESCRIPTION

FIG. 1 is a perspective view of an expansion part for an orthopedic device.

FIG. 2 is a second perspective view according to the expansion part of FIG. 1.

FIG. 3 is a front elevational view according to the expansion part of FIG. 1.

FIG. 4 is a rear elevational view according to the expansion part of FIG. 1.

FIG. 5 is a first side elevational view according to the expansion part of FIG. 1.

FIG. 6 is a second side elevational view according to the expansion part of FIG. 1.

FIG. 7 is a top plan view according to the expansion part of FIG. 1; and,

FIG. 8 is a bottom plan view according to the expansion part of FIG. 1.

The broken lines illustrate environmental structure of the expansion part for an orthopedic device and form no part of the claimed design.
